UNITED STATES PATENT OFFICE.

LYMAN WATERMAN, JR., OF CRESTON, IOWA, ASSIGNOR, BY MESNE ASSIGNMENTS, OF ONE-HALF TO WILLIAM H. DOTY AND CHARLES W. DOTY, OF GALESBURG, ILLINOIS.

COMBINED CHECK-ROWER AND SELF-DROPPING CORN-PLANTER.

SPECIFICATION forming part of Letters Patent No. 328,160, dated October 13, 1885.

Application filed April 30, 1885. Serial No. 163,917. (No model.)

To all whom it may concern:

Be it known that I, LYMAN WATERMAN, Jr., of Creston, in the county of Union and State of Iowa, have invented a new, useful, and Improved Combined Check-Rower and Self-Dropping Corn-Planter, of which the following is a description, reference being had to the accompanying drawings, in which—

Figure 1 is a plan view. Fig. 2 is a side view. Fig. 3 is a vertical sectional view taken upon the line $x-x$, Fig. 1, viewed in the direction of the arrow there shown. Fig. 4 is a detail view of the inner end of one of the wheel-hubs, showing the ratchet mechanism for operating the check-rower, the axle being likewise shown in section. Fig. 5 is a longitudinal sectional view in detail of said hub, ratchet, and check-rower mechanism, taken upon the line $y-y$, Fig. 4, viewed in the direction of the arrow there shown; and Fig. 6 is a vertical sectional view in detail upon the line $z-z$, Fig. 1, viewed in the direction of the arrow there shown, of the mechanism by which the dropper is operated.

Like letters of reference indicate like parts in the different figures.

The object of my invention is to provide a combined check-rower and self-dropping corn-planter, the former or marking feature of which may be operated by means of the revolution of the wheels, while at the same time said device may be made adjustable to provide for variations which may occur by reason of irregularities in the surface of the ground to be planted, thus enabling the operator to change said machine while in use, to compensate for such variations as may be caused by said surface irregularities, and to keep the cross-rows straight.

In the drawings, A represents the frame of the machine, to which bearings a , Fig. 5, are attached, and into which the axle B is loosely secured. The runners C C, with the customary seed-boxes $c-c$ and dropping mechanism, are attached in the usual manner to the cross-bar A' of the frame. Suitable shoulders—one of which is shown at b , Fig. 5—are attached to the axle to prevent a longitudinal movement thereof, while ratchet-wheels B' B' are

likewise rigidly attached to said axle, forming shoulders for the spindles upon which the wheels D are placed. Pawls d —one of which is shown in Figs. 4 and 5—are loosely attached to the hubs D' D', and held in engagement with the ratchets B' B' by springs $d-d$, so that when the wheels D are revolved in the direction of the curved arrows shown in Fig. 4, the axle B is caused to revolve in unison therewith. This arrangement enables the wheels to rotate in an opposite direction without moving the axle; or the axle may be turned in a forward direction while the wheels remain stationary. Upon the respective ends of the axle-spindles I place one or more, but preferably three, radial markers, E, the ends of the spindles being squared, as shown in Fig. 5, to receive said markers, which are attached thereto by means of nuts e , so that said markers, which are preferably constructed as shown in Fig. 2, are caused to revolve with the axle.

To enable the machine to be driven upon hard ground without injury to the markers, I make the main arms thereof somewhat shorter than the radius of the wheel, and add thereto jointed extensions $e'-e'-e'$, which may be attached by means of bolts and nuts $e^2-e^2-e^2$, upon loosening which said extensions may be reversed, and the markers thus shortened; but in actual use they are extended, as in Figs. 1 and 2.

To enable the operator to turn the axle independently of the wheels, and thus adjust the markers E to any desired position, I attach a ratchet-wheel, F, Figs. 1 and 3, to the axle B, adapted to be engaged by a pawl, g, attached to a hand-lever, G, Figs. 1, 2, and 3, the lower end of which is loosely secured to said axle. Upon reciprocating said lever the axle may be revolved to any extent desired independently of the wheels, and the markers E may be thus placed in line at any time with the cross-rows.

Keyed to the axle is a gear-wheel, H, which engages a secondary gear-wheel or pinion, J, rigidly attached to a shaft, j, provided with cam-shaped arms K K, Figs. 1, 3, and 6, the extremities of which are curved in opposite directions, as shown in Fig. 3, while they

likewise have an opposite lateral inclination in a plane oblique to the axis of the shaft j , as clearly shown in Fig. 6.

A drop-lever, L , pivoted to the cross-bar A' at l , and one end of which is connected by a pin or bolt, l' , to the drop slide or bar l'' , is preferably provided upon its opposite end with a friction-roller, l'' , which is adapted to be alternately engaged by the arms $K K$ as the shaft j is revolved, thus reciprocating the bar l'' . The wheels $H J$ should be so proportioned in size as to produce a half-revolution of the shaft j and a corresponding movement of the slide l'' with each respective impression in the soil of the markers e' . The bearing of the shaft j is capable of being moved in the frame A by means of a lever, M , which is pivoted to a suitable bracket or support attached to said frame, as at m , Fig. 6, the shaft j passing loosely through the lower end of said lever. By moving said lever M backward or forward the gear-wheel J may be thrown out or into mesh with the wheel H . To lock the same in one or the other position, as required, a spring-catch, m' , Fig. 2, may be attached to the lever M , which may engage in the usual manner in notches formed in an arch or guard, m^2 , bolted to the frame A . An adjustable seat, N , bolted to a support, n , the bolt of which is adapted to be moved back and forth in a slot in said support, may enable the operator to balance the runners C , and to raise and lower the same at will. By attaching the tongue O directly to the axle, and allowing a vertical play thereof within the guard o , Fig. 1, the raising and lowering

of the runners may be readily accomplished.

It is obvious that in the event of the markers being thrown out of line with the cross-rows, by reason of the unevenness of the surface, or from other causes, the same may at once be adjusted by a greater or less movement of the lever G , while the dropping mechanism, being controlled wholly by the revolution of the axle, is changed in a corresponding degree.

The advantages of said machine are that by it the rows may be checked with certainty and accuracy, while the dropping mechanism is automatic, thus dispensing with the services of an assistant.

I do not claim, broadly, herein any of the improvements patented to T. F. Tanner, June 10, 1879, nor to G. B. Vaughan, October 25, 1870.

What I do claim, and desire to secure by Letters Patent, is—

1. The combination of the axle B , arms E , wheels D , hub-ratchets B' , ratchet F , lever G , gears $H J$, arms $K K$ with lever L and drop bar l'' , all arranged and constructed substantially as described.

2. The combination, with the axle and wheels of a corn-planter, of the ratchets $B' B''$ and F , lever G , gear-wheels $H J$, shaft j , arms K with lever L , drop-lever l'' , and means, as the lever M , for throwing said mechanism in and out of gear, substantially as set forth.

LYMAN WATERMAN, JR.
